UNITED STATES PATENT OFFICE.

BENJAMIN DUBINSKI, OF NEW YORK, N. Y., ASSIGNOR, BY DIRECT AND MESNE ASSIGNMENTS, TO STANDARD LIGHTERS MANUFACTURING CO., OF NEW YORK, N. Y.

POCKET-LIGHTER.

1,026,571.

Specification of Letters Patent.

Patented May 14, 1912.

Application filed January 13, 1911. Serial No. 602,481.

To all whom it may concern:

Be it known that I, BENJAMIN DUBINSKI, a citizen of the United States, residing at New York, in the county of New York and 5 State of New York, have invented a new and useful Pocket-Lighter, of which the following is a specification.

It is the object of the present invention to provide an improved pocket lighter, of that 10 type embodying a wick and a hinged cover which is to be released by a press button and swings back, to expose the wick, an igniting device for the wick being at the same actuated.

15 One aim of the present invention is to so relatively arrange the igniting device for the wick, and the cover for the device, that actuation of the former will serve to open the latter, the employment of a separate 20 spring for swinging the cover open, being thus obviated. Ordinarily, pocket lighters of this type embody, in their igniting means, a pyrophoric element and a friction element co-operating therewith and it is customary to dispose behind the pyrophoric element a spring which holds it yieldably in engagement with the friction element. This is also done in the instance of the present 25 invention and means is provided for adjusting the tension of the spring so that the pyrophoric element may be caused to bear more or less firmly against the friction element and its proper action thus be insured. One objectionable feature of devices of this 30 type is that ordinarily gasoline is employed as a fuel and the odor from the gasoline is not prevented from escaping beneath the cover of the lighter.

The present invention therefore contemplates embodying in the structure of the 35 lighter, means for snuffing the wick and so constructing such means that it will effectually prevent the escape of gasoline or other fuel from the fuel containing body of the 40 device.

In the accompanying drawings: Figure 1 is a perspective view of a pocket lighter constructed in accordance with the present invention. Fig. 2 is a vertical longitudinal 45 sectional view therethrough. Fig. 3 is a similar view the parts being illustrated in actuated position. Fig. 4 is a sectional view on the line 4-4 of Fig. 2. Fig. 5 is a view similar to Fig. 2 illustrating a slight modi-

fication of the invention. Fig. 6 is a view 55 similar to Fig. 2 illustrating a further modification of the invention. Fig. 7 is a horizontal sectional view on the line 7-7 of Fig. 6.

In the drawings, the device is illustrated 60 as embodying a hollow body 10 which is preferably similar in shape and size to the body of an ordinary pocket match safe and this body is filled with a quantity of cotton 11 or other similar absorbent material which 65 is saturated with the fuel, such as gasoline or alcohol, which is poured into the body through a filling opening 12 in the front side of the body, this opening being normally closed by a plug 13 threaded therein. 70 A wick tube indicated by the numeral 14 is threaded through the upper end of the body 10 and fitted in the tube is a wick 15 the upper end of which projects a slight distance above the upper end of the tube and 75 the lower portion of which extends into the mass of absorbent material 11 within the body. A collar 16 is fitted upon the tube 14 and a packing washer 17 of rubber or other suitable material is also fitted upon 80 the tube. The cover for the device is indicated by the numeral 18 and is hinged at its rear as at 19 to the upper end of the body 10. A spring catch 20 is arranged within a socket at the front of the body 10 and has a 85 press button 21 which projects through an opening in the front wall of the body. The upper end of the catch engages with a lug upon the cover 18 and serves to normally hold the cover closed. At its front and 90 beneath its top, the cover is formed interiorly with a boss 22, the function of which will be presently explained.

Formed upon the top of the body 10 are spaced ears 23 from one of which projects 95 a stop 24. Between the ears 23 there is pivotally mounted a friction element including a head 25 and a finger 26. The head 25 is formed with a lug 27 which is designed to engage with the stop 24 when the head 100 has been rotated to substantially the position shown in Fig. 3 of the drawing, whereby to prevent further movement of the head in this direction. A spring 28 is disposed upon a pin 29 which is secured at its ends in 105 the ears 23, and this spring is held in an opening 30 in the head 25 and is secured at one end to one of the ears 23 and at its

other end engages as at 31 beneath the finger 26. This spring normally tends to throw or rotate the head rearwardly and thereby spring the finger 26 from the position shown in Fig. 2 of the drawings to the position shown in Fig. 3 therecf. By referring to Fig. 2 of the drawings it will be observed that the upper edge of the finger is curved and bears against the boss 22 within the 10 cover 18, when the cover is closed. As soon however as pressure is exerted upon the press button 21, the catch 20 will be disengaged from the cover 18 and the spring 28 will tend to swing or rotate the head and 15 its finger upwardly in a rearward direction. Inasmuch as the upper edge of the finger 26 bears against the boss within the cover 18, the cover will be swung open as the head and its finger is rocked or swung upwardly. It will be noted at this point that 20 the spring 28 therefore constitutes not only a means for swinging the finger 26 upwardly rearwardly but also as a means for swinging the cover to open position when 25 released. By this arrangement of parts, the provision of a separate and distinct spring for swinging the cover to open position is obviated. For a purpose to be presently explained, the head 25 has its under edge 30 formed with teeth 32. These teeth 32 all project forwardly.

A tube 33 is secured in the body 10 and at its upper end opens through the said body and at its lower end is closed. Fitted 35 in the tube at the upper end thereof is a plug 34 of any suitable pyrophoric material. Fitted within the tube 33 is a spring 35 which at its lower end bears against the lower closed end of the tube and its upper 40 bears against the pyrophoric plug 34 and holds the same yieldably in engagement with the toothed under edge of the head 25 of the friction element. At this point it will be readily understood that when the 45 press button 21 is pressed upon cover 18 will be forced open by the upward rearward swinging movement imparted to the head and finger of the friction element through the medium of the spring 28. This 50 movement of the friction member will result in its toothed lower edge riding over the upper end of the pyrophoric plug and as a result, sparks will be produced which will ignite the wick 15.

55 In the form of the invention shown in the first four figures of the drawing, the finger 26 of the friction element is formed upon its under side at its free end with a snuffing cap 36 which fits over the upper 60 end of the wick tube 14 and wick 15 therein, when the friction element is in the position shown in Fig. 2 of the drawings. The edge of the open end of this cap will bear, when the friction element is in such position, 65 against the packing washer 17 and serve to

prevent the escape of fumes from the fuel within the body 10.

In the form of the invention shown in Fig. 5 of the drawings, the snuffing cap 36 is omitted from the finger 26 and the end 70 of this finger is brought to bear directly against the upper end of the tube whereby to extinguish the flame when the cover of the device is closed. Otherwise, the structure is the same as that shown in the first 75 four figures of the drawings.

In the form of the invention shown in Figs. 6 and 7 of the drawings, a tube 37 is arranged within the cover 18 and is designed to coöperate with the upper end of 80 the wick tube and the projecting end of the wick to serve to snuff the flame when the cover is closed. In order to accommodate this tube, the finger is off-set at one side and as clearly shown in Fig. 7 of the drawings. 85 In this form of the invention, instead of permanently closing the lower end of the tube 33, it is closed by a screw plug 38 which is adjustable in the tube, it having its grooved end presented at the bottom of the 90 body 10, whereby to adjust the tension of the spring 35 and thereby cause the pyrophoric plug to bear with greater or less force against the toothed or serrated edge of the friction element. 95

What is claimed is:—

1. In a device of the class described, a fuel container, a wick carried thereby, a pyrophoric element carried by the container, and a spring actuated rotatable friction element coöperating with the pyrophoric element and having a projecting finger arranged at its free end to snuff the wick. 100

2. In a device of the class described, a fuel container, a tube carried thereby, a wick 105 fitted in the tube, a packing element fitted around the tube, a pyrophoric element carried by the container, and a spring actuated friction element coöperating with the pyrophoric element and having a portion arranged to fit over the tube and against the packing element. 110

3. In a device of the class described, a fuel container; a cover therefor; a pyrophoric element carried by the container; a friction 115 element, separate from the cover, and having an eccentric portion bearing slidably against the cover to open the same, the friction element coöperating with the pyrophoric element, and being journaled for 120 rotation upon the container; and a spring directly connected with the friction element to rotate the same, said spring constituting the sole means for moving the cover into an open position. 125

4. In a device of the class described, a fuel container; a cover hinged thereto; a tubular socket in the container; a pyrophoric element slidable in the socket; a friction element, separate from the cover, and having 130

an eccentric portion, bearing slidably against the cover to open the same, the friction element coöperating with the pyrophoric element, and being journaled for rotation upon the container; a spring in the socket, thrusting the pyrophoric element continuously against the friction element; and a second spring directly connected with the friction element, to rotate the same, the last men-

tioned spring constituting the sole means 10 for moving the cover into an open position.

In testimony that I claim the foregoing as my own, I have hereto affixed my signature in the presence of two witnesses.

BENJAMIN DUBINSKI.
